CLAIM

The ornamental design for a “carabiner with calculator”, as shown and described.

DESCRIPTION

FIG. 1 is a front view of a “carabiner with calculator” showing my design;

FIG. 2 is a rear side view thereof;

FIG. 3 is a right side view thereof;

FIG. 4 is a left side view thereof;

FIG. 5 is a top plan view thereof;

FIG. 6 is a bottom view thereof;

FIG. 7 is a perspective view thereof; and,

FIG. 8 is a front view in an alternate position.
